UNITED STATES PATENT OFFICE.

MARCELLIN DUPUY, OF NEW YORK, N. Y.

DESIGN FOR A WIRE FENCE.

Specification forming part of Design No. 5,297, dated October 3, 1871.

To all whom it may concern:

Be it known that I, MARCELLIN DUPUY, of the city, county, and State of New York, have invented a new and original Design for Wire Fence; and I do hereby declare that the following is a full, clear, and exact description thereof, which will enable others skilled in the art to make and use the same, reference being had to the accompanying drawing forming part of this specification.

The drawing represents a side view of my new wire fence.

This invention relates to a new form of wire fence produced by a series of crossing-wires, which are looped and interlocked on top, as is clearly shown in the drawing. It is made from wire of suitable thickness and of suitable size.

I claim as my invention—

The design for a wire fence, as shown.

MARCELLIN DUPUY.
